UNITED STATES PATENT OFFICE.

GEORGE VAN NAME, OF ST. LOUIS, MISSOURI.

ROLLER FOR GRINDING-MILLS.

SPECIFICATION forming part of Letters Patent No. 291,654, dated January 8, 1884.

Application filed April 26, 1883. (No model.)

To all whom it may concern:

Be it known that I, GEORGE VAN NAME, a citizen of the United States, residing at St. Louis, in the State of Missouri, have invented 5 certain new and useful Improvements in Rollers for Grinding-Mills, of which the following is a specification, reference being had to the accompanying drawings.

This invention relates to improvements in 10 rollers for Grinding-Mills; and it consists in the construction of the rollers, all of which will be hereinafter more fully described, and pointed out in the claim.

In the drawings accompanying and forming 15 part of this specification, Figure 1 is a longitudinal section of a roller, with blades arranged in grooves around the surface, parallel with the axis. Fig. 2 is a cross-section of the roller, showing the blades of hard and soft material. 20 Fig. 3 represents one of the blades detached. Fig. 4 is a side view of the cylinder without blades. Fig. 5 is an end view, showing the longitudinal grooves for keying the blades.

A is the shaft, on which the cylinder B is 25 made secure. Two or more dovetailed annular grooves, *b b*, are cut around the surface of cylinder B, and four longitudinal grooves, *e f g h*, are cut slightly dovetailed in the surface of the cylinder B. Blades of hardened 30 steel C C are formed with dovetailed tongues *c' c'*, to correspond with the grooves *b b*. There are also blades C' C', of the same form, made of any softer material—as soft iron, hardened paper, wood, &c.—to be placed alternately 35 with the steel blades. These blades C and C'

are inserted by dropping them into, or sliding them endwise in, the longitudinal grooves *e f g h*, and the dovetailed tongues are entered into grooves *b b*, and moved around the cylinder B. The surface of the roller is made up each 40 way from these grooves, until each quadrant is full, leaving room only for four key-blades, which are dovetailed to fit the grooves *e f g h*, and driven in endwise, thus keying securely 45 the blades in the four quadrants of the cylinder B. Should any blade or blades require removal, it will be seen that by this construction it will be but little trouble to remove it or them without disturbing either of the other sections beyond the longitudinal grooves nearest the defective blades. 50

I am aware that rollers for grinding-mills have been constructed of alternate blades of hard and soft material, and such, broadly, I do not claim. 55

I claim—

A grinding-roller for mills the surface of which is composed of alternate series of thin steel blades and softer material, secured in the cylinder by dovetailed grooves in the 60 surface of the cylinder, and keyed together by key-blades lengthwise of the roller, substantially as and for the purpose described.

In testimony whereof I affix my signature in presence of two witnesses.

GEO. VAN NAME.
